United States Patent Office.

HENRY SCHOFIELD, OF PHILADELPHIA, PENNSYLVANIA, ASSIGNOR TO HIMSELF AND CHARLES D. CLARKE, OF SAME PLACE.

Letters Patent No. 97,817, dated December 14, 1869.

IMPROVEMENT IN STONE-POLISHING MACHINE.

The Schedule referred to in these Letters Patent and making part of the same.

Be it known that I, HENRY SCHOFIELD, of the city and county of Philadelphia, and State of Pennsylvania, have invented new and useful Improvements in Machines for Rubbing Marble, Brownstone, Granite, Slate, Freestone, Sandstone, and other similar material; and I do hereby declare that the following is a full, clear, and exact description of the same, reference being had to the annexed drawings, making part of this specification, and to which reference will be made by letters.

Of said drawings—

Figure 1 represents my improved machine, as seen from the side;

Figure 2 represents the same, as seen from one end;

Figure 3 represents the rubbing-disk, as seen from above;

Figure 4 represents the under surface of said disk; and

Figure 5 represents said disk in section.

I will now proceed to describe my improved machine.

On a rectangular frame, A, supported horizontally on posts *a*, is a carriage, B, whose wheels *b* roll on ways or rails *b'*, placed lengthwise on the surface of the frame.

This carriage is intended for supporting the block of stone to be rubbed, and is moved backward and forward by a screw, C, which is supported in a bearing on a cross-bar, I, of the frame, and passes longitudinally underneath the carriage and through a nut, *c*, attached to the under surface of said carriage.

A shaft, E, which passes through and rests in bearings, let into the side-pieces of frame A, carries a pulley, (not shown in the drawings, but which may be conveniently placed on the end at the right hand, as seen in fig. 2,) to which power may be communicated by a crank, belt, or any other means.

On the opposite end of shaft E there are keyed a pulley, H, and a bevel-gear wheel, *g*, the latter gearing with one or the other of two similar gear-wheels, *g'* and *g''*, on a shaft, F, which is supported by brackets *h* and *h'*, outside of but parallel to the side of frame A.

The purpose of the bevel-gearing and the shaft last named, is to aid in the transmission of motion from the driving-shaft E to the carriage B, and in furtherance of this design the extremities *j* and *j'* of shaft F and screw C are connected by a band, J, which passes around two pulleys, (not shown in the drawings,) one of which is keyed to the shaft and the other to the screw.

It will thus be seen that if the bevel-wheels *g* and *g'* be geared together, as shown in fig. 1 of the drawings, and the shaft E be rotated in the direction indicated by the arrow marked on pulley H, the screw C will be caused to revolve from left to right, and thus to force the carriage B forward.

The carriage has, however, not only a movement forward, but also a movement backward, or, in other words, it reciprocates, the change of motion being effected automatically, and so as not to require the arrest of rotation of shaft E, in the following manner:

That portion of shaft F which supports the wheels *g* and *g'*, is made hollow, for the reception of a rod, *k*, to which said wheels are fastened by pins *l*, which pass through the hubs *l* of said wheels, through the rod *k*, and through the shaft F, the holes *k'*, through the latter, being elongated, so as to admit of a slight reciprocating movement of the rod, and thus also of the wheels.

To the outer end of rod *k* is attached, by a swivel-joint, another rod, *m*, bent in such manner as to lie for some distance parallel to and against the side of frame A, and thence upward, so that its vertical extremity may stand directly in the path of two stops, *m*, (of which one only is seen in the drawing,) which project from the side of carriage B, thus, when the carriage is moving in the direction indicated by the arrow, (seen upon its side in fig. 1,) one of the stops will be brought in contact with the vertical extremity of rod *M*, and force it, together with rod *m* and the two wheels, *g* and *g'*, forward, bringing the wheel *g''* into connection with wheel *g*, on shaft E, and thus reverse the direction of shaft F, and consequently of the screw C; and, on the return of the carriage, just the reverse will happen; the wheel *g''* will be thrown out of connection, and the wheel *g'* into connection with wheel *g*, and thus similarly reverse the direction of rotation of screw C.

The rubbing-device is a circular disk, N, (shown in figs. 3, 4, and 5,) to which is imparted a movement of rotation, and which is adjustable, within certain limits, to various inclinations and curvatures of the surface of the stone to be ground, as well as to a horizontal surface.

The disk is made of metal, with a central orifice, *n*, through it, surrounded on its upper surface, by a hub, *n'*, and a raised flange, *n''*, encircling said hub at some distance from it, which, together with the hub and disk, form an annular basin for the reception of a mixture of sand and water, or other material required to be used for rubbing-stone, &c.

To conduct the sand and water to the surface of the stone, a series of holes, *o*, is made through the disk, at points adjacent to the hub, or through the centre of the upright shaft, which holes communicate with as many radial channels formed in the under surface of the disk.

The disk is keyed upon the lower end of an upright shaft, O, supported in bearings on a swinging frame, P, composed of two side-pieces, *p* and *p'*, and two cross-bars, *p''* and *p'''*.

The lower ends of the side-pieces are bolted to the

sides of two worm-wheels, Q, which turn loosely on the two ends of shaft E, and with these worm-wheels are geared screws q, formed upon or fastened to the upper ends of two short inclined shafts, q', each having upon its lower end a bevel-gear wheel, r, which gears into similar bevel-wheels r' on a transverse shaft, R, which turns in bearings attached to the under surfaces of the side-pieces of the frame, and has upon it, at one end, a hand-wheel, S.

It will be readily seen that by means of the combination of devices last described, it is only necessary to turn the hand-wheel S to the right or left to cause the frame P to swing forward or backward, and thus adjust the disk N to different inclinations.

The shaft O turns in journal-bearings attached to the bars p' p" of the frame P, its weight, as also that of the disk, being sustained by the cross-bar p", through the medium of a fixed collar, V, on said shaft, which rests on the upper surface of slide-bar, and rotary motion is communicated to said shaft through the medium of a bevel-wheel gear, S, keyed upon its upper end, and resting on the upper surface of bar p', and a similar wheel, S', which gears into it, keyed upon one end of a short horizontal shaft, T, which is supported in bearings projecting from bar p', and has upon its outer end a pulley, U, to which power is transmitted from the pulley H by means of a belt, u.

It is essential that the rubbing-disk be adjustable to different altitudes, in order to accommodate it to blocks of stone of different thicknesses, and to this end I have adopted the following construction and combination of mechanism, premising that shaft O has a longitudinal slot, o", in its surface, into which projects a feather on wheel, S, so that said shaft may be moved up or down in its bearings, without disturbing wheel S, otherwise than to cause it to rotate.

The cross-bar p", which, as has already been said, supports the weight of shaft O and disk N, is in its turn supported by the side-pieces p of the frame, through the medium of two screw-bolts, z, one at each end, which may clamp said bar to the side-pieces at any point between the two extremities of longitudinal slots x' in said side-pieces, through which they pass.

Two large screws, W, each with a bevel-gear wheel, y, keyed upon its upper end, and resting on a collar or washer on the upper surface of the bar p', pass downward through both bars p' and p", loosely through the former, and through fixed nuts in the latter.

These screws serve to adjust bar p" to different elevations, thin gear-wheels, y, gearing with similar wheels, z, on a short horizontal shaft, z, supported in bearings z, on bar p', and which carries, upon one end, a hand-wheel, X.

Thus, by loosening the nuts on the screw-bolts z, the bar p", and, with it, the shaft O and disk N, may be readily adjusted to different heights, by simply turning hand-wheel X, and be secured at any elevation adjusted to, by again tightening up the nuts.

In order to raise, for temporary purposes, the rubbing-disk from the surface of the stone without having to revert to the use of screws W, as well, also, as to relieve the stone of too great a weight, two levers w, supported on fulcrums w', on the upper surface of cross-bar p", engage, at one end, with the grooved collar V on shaft O; and on the outer end of one of these levers is a metallic balance-weight, w", which may be either interchangeable with other bodies of greater or less weight, or be made adjustable on said lever, while the outer extremity of the other lever may be grasped by the hand.

It is obvious that other methods of construction may be adopted for conveying the sand and water to the surface of the block. Thus, the shaft to which the disk is attached may be tubular, and communicate with a cavity formed in the rubbing-surface of the

disk, at and around its axis of rotation, and this tubular shaft may be made the channel through which to supply the rubbing-material. This, however, possesses no novelty. But there are other methods of construction which I propose to use, and which have not, I believe, been known or used by others, namely, such as shall convey the sand and water from a tubular shaft, or from a receptacle surrounding the shaft, through radial channels formed on the upper surface of the disk, or through radial channels formed wholly in the solid metal of the disk, said channels, whether on the surface or within the body of the metallic disk, communicating with its rubbing-surface, and with the block or slab, by a series of small lateral holes.

Either of these methods of construction, as well as that exhibited in the drawings, I regard as greatly superior to those heretofore employed; but, superior as they may be, I attach less importance to them than to the use of a plain-surfaced metallic rubbing-disk, substantially such as I have described, whatever may be the method adopted for supplying it with rubbing-material.

Rotating metallic disks have, I am aware, been used to cut or plane the surface of marble or other stone, said disks being furrowed on their working-surface, and presenting a projecting cutting-edge, extending from the margin of the central cavity, in spiral convolutions, to the periphery; and I am aware, also, that there have been used rotating rubbing-disks composed of blocks of stone keyed or otherwise clamped together in an iron case. My disk is, however, essentially different from both of these in construction, and from one of them in purpose as well as construction.

In the first place, it is not intended, and cannot be used to plane or cut of itself. Its office is simply to rub—that is to say, to press the sand down upon the surface of the block, and, by its rotating movement, force the particles of sand around, and outward toward its periphery, in order that, in their movement, while subjected to pressure, said particles may abrade or rub down the surface of the block or slab. Its operation is essentially that of rubbing or grinding. No part of it is designed to be brought in contact with the block, and whatever of cutting may be produced is effected by the particles of sand alone, not by any part of the disk itself.

In the second place, it is essentially different in construction from and superior to a rotating disk made up of blocks of stone. The difference in construction is so manifest as not to require further remarks; but some of the advantages possessed by a metallic disk over a stone disk for the purpose of rubbing marble or stone may be briefly enumerated as follows:

First. A metallic disk is much less expensive, may be made by casting in a mould, and thus be readily and cheaply replaced by another when too much worn.

Second. It is impossible for it to get out of order, and to require repairs, whereas a disk made up of a number of blocks of stone requires constant care and frequent adjustment, in order that the blocks, from unequal wear, due to unequal hardness, may, as uniformly as possible, present an even or plain rubbing-surface.

Third. It is vastly more durable. A disk of metal, cast in iron or other chill-moulds, is but slightly acted on by the particles of sand, so long as their resistance to it is based upon a comparatively soft support below, such as marble or other building-stone, while, on the contrary, a stone disk will be abraded in an equal degree to the block on which it is operating.

Fourth. It is much more economical of power, for, while, with it, nearly all the power employed is directly utilized in reducing the block or slab operated on, in the use of a stone disk, as much power is expended in the reduction of the disk itself as in the reduction of the block.

Fifth. Its weight being so much less than that of a composite stone disk, it requires much less power and less complicated machinery to adjust it, a hand-lever being quite sufficient for the purpose.

Having thus described my invention,

What I claim as new, and desire to secure by Letters Patent, is—

1. In a machine for rubbing blocks or slabs of marble, &c., the combination of the reciprocating carriage, for supporting the block or slab, a rotating rubbing-disk, composed entirely of metal, and having a smooth or plain rubbing-surface, substantially as described, and mechanism for adjusting and supporting said disk at different elevations, corresponding to the thickness of the block or slab to be rubbed, the combination being and operating substantially as herein set forth.

2. In a machine for rubbing blocks or slabs of marble, &c., the combination of the reciprocating-carriage, for supporting the block or slab, a rotating metallic rubbing-disk, with a plain rubbing-surface, and weighted balance-lever, or equivalent device, for graduating the pressure of the disk upon the block or slab, the combination being and operating substantially as herein set forth.

3. In a machine for rubbing blocks or slabs of marble, &c., the combination of the reciprocating carriage for supporting the blocks or slabs, a rotating metallic rubbing-disk, and hand-lever, for elevating said disk temporarily above the surface of block or slab, the combination being and operating substantially as herein described.

4. In a machine for rubbing blocks or slabs of marble, &c., the combination of the reciprocating carriage, for supporting the block or slab, with a rotating rubbing-disk, connected to a swinging frame, and made capable thereby of adaptation to surfaces that are curved, inclined, and horizontal, the combination being and operating substantially as herein set forth.

5. In a machine for rubbing blocks or slabs of marble and other stone, a rubbing-disk, the rubbing-surface of which is of metal, entirely plain—that is to say, free from a protruding shaft, and from angular projections or protuberances—perforated, for the passage of sand and water, and connected, on its back or reverse surface, to the extremity of a shaft, through the medium of which power is communicated, for rotating said disk, and for elevating it, to suit blocks or slabs of different thicknesses, all substantially as described.

6. The combination, substantially as described, or its equivalent, of the revolving gear-wheel *g*, gear-wheels *g' g''*, rods *k* and *M*, shaft *F*, screw *O*, carriage *B*, and stops *m*, for the purpose set forth.

7. The combination, substantially as described, or its equivalent, of the revolving gear-wheels *r'* and *r*, shaft *g'*, and screws *q*, worm-wheels *Q*, and swinging frame *P*, for the purpose herein set forth.

HENRY SCHOFIELD.
